UNITED STATES PATENT OFFICE.

THOMAS A. BARNES, OF PASADENA, CALIFORNIA.

DESIGN FOR A PIANO-STOOL.

45,365.

Specification for Design.

Patented Mar. 10, 1914.

Application filed January 2, 1914. Serial No. 810,076. Term of patent 7 years.

To all whom it may concern:

Be it known that I, THOMAS A. BARNES, a citizen of the United States, residing at Pasadena, in the county of Los Angeles and State of California, have invented a new, original, and ornamental Design for Piano-Stools, of which the following is a specification, reference being had to the accompanying drawing, forming part thereof.

In the drawing, Figure 1 is a plan, and Fig. 2 an elevation of my design.

I claim:

The ornamental design for a piano stool, as shown.

THOMAS A. BARNES.

Witnesses:

FRED A. MANSFIELD,
FORD W. HARRIS.
